WRAPPING DEVICE.

1,364,093.

Specification of Letters Patent.

Patented Jan. 4, 1921.

Application filed May 5, 1920. Serial No. 379,063.

To all whom it may concern:

Be it known that we, JOHN E. FILLINGAME and JOSEPH M. RIDEOUT, citizens of the United States, residing at Washington, in the District of Columbia, have invented new and useful Improvements in Wrapping Devices, of which the following is a specification.

This invention relates to a device primarily designed for use in pasting and applying wrappers to magazines and other periodicals for transportation through the mails, and by means of which paste or like adhesive employed may be automatically applied to the wrappers and the latter properly tensioned or drawn taut about the publication during the wrapping operation.

The primary object of the invention is to provide a wrapping device whereby the paste may be automatically applied successively to the wrappers as they are used, whereby the amount of time and labor required in applying the adhesive to the wrappers by means of a brush may be reduced and the wrapping operation considerably simplified and expedited.

A further object of the invention is to provide means for supporting a pile or stack of wrappers of any desired thickness, in connection with a reservoir for the paste which is adjustable to permit any desired number of wrappers to be placed thereunder and is adapted to feed downward by gravity to effect the application of paste to the successive wrappers.

A still further object of the invention is to provide means whereby a prescribed amount of paste may be applied to the end of the wrapper to be pasted, and whereby in the process of applying the wrapper to a magazine the wrapper will be drawn as taut as desired and the paste automatically applied thereto.

With these and other objects in view, the invention consists of the features of construction, combination and arrangement of parts, hereinafter fully described and claimed, reference being had to the accompanying drawings, in which:

Figure 1 is a top plan view of a wrapping device embodying the invention.

Fig. 2 is a side elevation of the same, showing in dotted lines the movement of the wrapper for applying it to the maga-

zine and actuating the paste hopper for the application of paste.

Fig. 3 is a section taken longitudinally of the device through the hopper, showing the same in normal position.

Fig. 4 is a view similar to Fig. 3 showing the hopper tilted for the paste spreading action.

Fig. 5 is a sectional elevation showing certain features of construction.

The device comprises a base board or plate 1 of suitable size and form to support a pile or stack of wrappers 2, which are arranged in superposed relation thereon so as to be successively withdrawn for use one by one from the top of the stack.

The end edges of the end portions 3 of the wrappers, which form the pasted folds or flaps thereof, are arranged to abut against a vertically and transversely disposed gage or stop plate 4 having a base portion or plate 5 provided with slots 6 for the passage of screws or like fastenings 7, whereby the gage plate is adjustably secured to the top of the base 1. By the adjustment of this gage or stop plate 4 the wrappers may be adjusted and positioned with reference to the paste discharge outlet of a paste hopper or receptacle 8 so as to vary the amount of the end portion 3 of each wrapper exposed for the application of paste thereto.

The hopper or receptacle 8 contains the paste or other adhesive 9 which is to be dispensed, and which is of sufficient fluidity to enable it to be applied and spread in a desired manner. The hopper 8 is made of metal or other suitable material and extends transversely of the base 1 and is of a length approximating the width of the wrappers 2. As shown, the hopper is open at top for the convenient replenishment of the paste whenever required and is approximately V-shaped in cross section, its sides converging in a downward direction to provide a constricted outlet 10. This outlet 10 is controlled by a valve or closure member 11, in the form of a substantially circular body of rubber or other elastic material which is adapted when depressed to snugly fill the outlet 10 and cut off the outflow of the paste therethrough. The valve 11 is carried by a plunger stem 12 slidably adjustable in a guide 13 on the front wall of

the hopper and provided with a notch or finger piece 14 whereby the valve may be raised and lowered. When the valve 11 is raised to open position it bears against the 5 adjacent front wall of the hopper, and this bearing contact and the frictional engagement of the stem 12 with the opening in the guide 13 maintains the valve in open position until it is forcibly depressed to closed 10 position.

The end walls of the hopper are provided with apertured brackets 15 which slidably engage and embrace a pair of posts or standards 16 between which the hopper is arranged. 15 By this arrangement the hopper is guided for movement between the posts in a vertical plane, allowing it to be elevated manually to permit a stack of wrappers to be placed beneath the same and also adapting the 20 hopper to move downward by gravity so as to rest upon the upper wrapper of the stack and so as to gradually and automatically descend as the wrappers are successively removed, to always dispose the outlet 10 in 25 position to apply the paste to the wrapper which is in uppermost position. For the purpose of holding the hopper elevated while a fresh supply of wrappers is being placed in position for use, spring actuated 30 dogs or latches 17 are provided upon the brackets 15 for engagement with keeper recesses 18 in the posts or standards 16, whereby the hopper may be held in raised position, leaving both hands free to apply and 35 adjust the wrappers or to perform other incidental operations, it being understood that before the hopper is so elevated the valve 11 is forced downward to close the outlet 10 against the discharge of paste. After the 40 wrappers are placed in position for use and the hopper supplied with a suitable quantity of paste, the latches 17 are released and the hopper allowed to descend until its 45 lower end rests upon the upper wrapper of the stack, whereupon the valve 11 is elevated to open position. The paste thus descends by gravity and issues through the outlet 10 so as to come in contact directly with the underlying surface of the end portion 3 of 50 the upper wrapper member 2, in readiness for a spreading application of a required amount of paste thereto.

The openings in the brackets 15 are of a size to allow said brackets to loosely embrace the posts or standards 16, thus adapting the hopper 8 to tilt or rock in a forward and rearward direction on said posts or standards. For the purpose of governing or regulating the degree of this tilting 55 movement the brackets are provided with depending arms 19 carrying adjustable stop screws 20 to engage the posts or standards 16, whereby the tilting motion of the hopper may be regulated to an exact degree as may 60 be required for any desired paste applying 65

action. Attached to the forward portion of the hopper and projecting beyond the front wall thereof at a downward and forward angle is a U-shaped bracket 21 carrying a transverse guide and tensioning roller 70 22 which normally rests upon the upper wrapper of the stack at a point in advance of the hopper. The weight of this bracket, and that of the valve, serves by gravity to normally tilt the outlet portion of the 75 hopper rearwardly, to the position shown in Fig. 3, in which position the lower edge 23 of the front wall of the hopper bears upon the surface of the upper wrapper, while the lower edge 24 of the rear wall of the 80 hopper is elevated slightly above the surface of said wrapper, this arrangement allowing the paste to come in contact with the front of the wrapper in line with the outlet 10 and beneath the wall edge 24 as will be 85 readily understood. The hopper 8 is adapted to be tilted during the wrapping operation in the opposite direction, as shown in Fig. 4, thus elevating the front edge wall 23 and depressing the rear edge wall 24 of 90 the outlet 10, for a purpose presently described. In this operation the lower portion of the hopper tilts forwardly and rollers 25 are provided upon the end walls of the hopper to limit such tilting movement. 95 These rollers are journaled upon axes arranged in rear of the vertical longitudinal center of the hopper and are adapted to engage the surface of the uppermost wrapper for the purpose described while permitting, 100 by their rolling action, free outward movement of the portion 3 of the wrapper from beneath the hopper during the application of the paste to the wrapper and the application of the wrapper to the magazine or 105 article 26 to which the wrapper is being applied.

In practice the wrappers 2 may be previously addressed in any suitable manner, and the addressed sides of the wrappers are arranged to face downward and the stack of wrappers placed in position upon the base 1 with the end edges of their portions 3 disposed to bear upon the gage 4, which is adjusted to the proper position to regulate the 110 amount of such end portion disposed for the application of the paste thereto. The hopper 8, having been supplied with a store of paste, is brought to rest upon the upper wrapper of the stack and the valve 11 115 opened to allow the paste to come into direct contact with the underlying surface of the wrapper. The magazine or article 26 is then laid in position upon the outer or forward end portion of the wrapper and the 120 extremity 27 of the latter turned over, as indicated in Fig. 2, and either disposed upon the outer surface of the magazine or between the leaves thereof, after which the 125 magazine, with the portion 27 of the wrap- 130

per applied thereto, is folded over upon the body of the wrapper, as shown in dotted lines in Fig. 2, while the magazine and body of the wrapper are at the same time raised 5 from the body of the stack, the arrangement thus being such that upon drawing the end portion 3 of the wrapper outwardly with the paste applied thereto and bringing the partially unwrapped magazine down- 10 ward upon the face of the stack, the end portion 3 may be folded over upon the previously folded body portion of the wrapper and pasted thereto to complete the wrapping operation. When the partially folded wrap- 15 per and magazine are elevated to the dotted line position shown in Fig. 1, at an angle to the end portion 3 of the wrapper, pressure will be applied to the roller 22 carried by the bracket 21 to lift the same, and said 20 roller and bracket will thereby be caused to perform the function of a crank arm or lever, by means of which the hopper 8 will be tilted from the normal position shown in Fig. 3 to the paste spreading position shown 25 in Fig. 4. The operator then draws end portion 3 of the wrapper outwardly from beneath the hopper during the motion of folding the outer portion of the wrapper initially about the magazine 26, the resist- 30 ance of the portion 3 of the wrapper to outward movement being sufficient to cause a tension to be applied to the wrapper during the folding operation, whereby the wrapper will be drawn tautly about the magazine. 35 In such paste applying position of the hopper 8, the edge 24 of the rear hopper wall is depressed into engagement with the surface of the wrapper, while the edge 23 of the front wall of the hopper is on the contrary 40 elevated from engagement with the wrapper. Hence it will be understood that as the end 3 of the wrapper is drawn outwardly, during which the adjacent portion of the wrapper runs easily in engagement 45 with the turning roller 22, the edge wall 24 will serve as a guiding edge holding the end 3 of the wrapper depressed while the paste is being applied thereto, while the edge 23 of the front wall of the hopper, being spaced 50 from the wrapper, will allow a certain amount of paste to flow from the outlet over the end portion 3, the amount of which is governed by the distance of the edge 23 from the surface of the wrapper, such edge 23 acting 55 as a scraper to remove any excess amount of paste. Thus as the wrapper is drawn outwardly a film of paste, of a depth or thickness varying according to the degree of elevation of the edge 23, will be applied to the 60 entire area of the portion 3 of the wrapper drawn beneath the outlet 10, whereby the paste may be automatically applied in a rapid and efficient manner and the application of an excess amount of paste to the 65 wrapper avoided. It will of course be un- derstood that by adjustment of the stop screws 20 the movement of the edge 23 in the tilting action of the hopper, and its distance from the surface of the wrapper may be regulated, thus enabling the depth or 70 thickness of the film of paste to be applied to the wrapper to be varied as desired or required under different conditions of service. After the portion 3 of the wrapper is withdrawn from beneath the hopper, it is 75 turned over upon the folded body of the wrapper and secured thereto to complete the wrapping operation, and thereupon the hopper tilts automatically back to the normal 80 position shown in Fig. 3 from the paste applying position shown in Fig. 4, in readiness for the application of paste to the next succeeding wrapper of the stack.

The device constituting the present invention will be found of special value in 85 saving time and labor in the wrapping of magazines and other publications commonly wrapped in a flat condition for transportation through the mails, the device saving considerable time and labor over the practice 90 commonly employed of hand-applying the paste by means of a brush to the end portions 3 of the wrappers, as well as diminishing the amount of time and labor required in the folding of the wrapper and 95 the application of the pasted edge to the body of the wrapper. With this device it is simply necessary to place a pile or stack of wrappers in position upon the base 1 and in proper relation to the hopper 8 and 100 to fold the wrapper successively about the magazine, the hand motion required in this operation effecting the tensioning of the wrapper to the desired tautness about the magazine and the automatic application of 105 paste to the free end of the wrapper, so that the wrapper may be quickly and conveniently folded over and secured. As the hopper 8 may be adjusted to different elevations, the number of wrappers contained 110 in the pile or stack disposed beneath the same may be varied, so that when required all wrappers of subscribers within a given territory may be placed in position for use at one time, thus enabling the wrapping 115 of magazines in accordance with a determined schedule to be conveniently carried out in a time and labor saving manner. It will be observed that the paste applying action of the device is such as to avoid the 120 waste of paste and at the same time insure the application of a proper amount of paste to the wrapper and no more. In addition to the time and labor saved in applying paste to the wrappers, additional time and 125 labor is saved in the use of this device in wrapping the magazines or other articles in such a way as to apply the wrapper with a desired degree of tautness, since in the folding motion described proper tension 130

will be automatically placed upon the wrapper by pressure of the roller 22 and the resistance of the end portion 3 of the wrapper to withdrawal in the pasting action, 5 thus enabling the wrappers to be snugly applied at all times without special effort or extra motion on the part of the operator. While the invention is set forth as being designed especially for use in wrapping magazines and other periodicals, it is to be understood that it may also be employed in the wrapping of any other articles for which it 10 may be found to be adapted.

Having thus fully described our invention, we claim:

1. In a wrapping machine, a base to support the wrappers, posts rising therefrom, and a hopper having a paste outlet in its bottom, said hopper slidably and pivotally 20 engaging said posts and adapted for tilting motion from normal to paste applying position in the withdrawal of a wrapper from beneath said outlet.

2. In a wrapping machine, a base to support the wrappers, posts rising therefrom, a hopper having a paste outlet in its bottom, said hopper being tiltably mounted on said posts, and means for tilting the hopper in the operation of withdrawing a wrapper 30 from beneath said outlet.

3. In a wrapping machine, a base to support the wrappers, supporting posts, a hopper having a bottom outlet provided with a front scraping edge and a rear guiding edge, 35 said hopper being slidably and tiltably supported upon said posts, and a guide member engageable by the wrapper and having a crank action to tilt the hopper to paste applying position in the operation of withdrawing the wrapper from beneath the hopper outlet.

4. In a wrapping machine, means for supporting a wrapper, a hopper having a paste outlet and tiltably mounted for movement from normal paste delivery to paste applying positions, and means operative upon the withdrawal of a wrapper from beneath the paste outlet to tilt said hopper to paste applying position.

5. In a wrapping machine, means for supporting a wrapper, a hopper having a paste outlet provided with a front scraping edge and a rear guiding edge, said hopper being tiltably mounted for movement from normal paste delivery to paste applying positions, and means operative upon the withdrawal of a wrapper from beneath the paste outlet to tilt said hopper to paste applying position.

6. In a wrapping machine, a base to support the wrappers, posts rising therefrom, a hopper having a paste outlet in its bottom, said hopper slidably and pivotally engaging said posts, and means for tilting the

hopper in the withdrawal of a wrapper from beneath the outlet.

7. In a wrapping machine, a base to support the wrappers, posts rising therefrom, a paste hopper having an outlet in its bottom provided with a rear guiding edge and a front scraping edge, said hopper slidably and tiltably engaging said posts, means for closing the hopper outlet, and means for transmitting tilting movement to the hopper in the withdrawal of a wrapper from beneath the outlet of the hopper.

8. In a wrapping machine, a base to support the wrappers, posts carried thereby, a hopper having a bottom outlet and slidably and pivotally engaging said uprights, the rear wall of the outlet forming a guide to bear upon the wrappers and the front wall of the outlet a scraper to remove excess paste from the wrappers, and an element carried by the hopper and engaged by the wrapper in the folding movement thereof for tilting said hopper to paste applying position.

9. In a wrapping machine, a base to support the wrappers, posts supported thereby, a hopper having a bottom outlet and slidably and tiltably engaging said posts, means for closing the hopper outlet, means for holding the hopper at an elevated position upon the posts, and means operative in the withdrawal of a wrapper from beneath the hopper for tilting said hopper to paste applying position.

10. In a wrapping machine, a base to support the wrappers, posts carried by the base, a hopper having a bottom outlet and slidably and tiltably engaging said posts, the front and rear walls of the hopper being provided respectively with a scraping edge to remove excess paste from the wrapper and a guiding edge to hold the wrapper down in its movement past the outlet, said edges being movable alternately into and out of working positions by the tilting movements of the hopper, and means adapted to be engaged by a wrapper which is being folded to tilt the hopper while the wrapper is being drawn outward from normal to paste applying position.

11. In a wrapping machine, a base to support the wrappers, posts rising therefrom, a hopper having a bottom outlet and slidably and pivotally engaging the posts for tilting movement from normal to paste applying position, rollers carried by the hopper to engage the wrappers and limit the tilting movement of the hopper, means for closing the hopper outlet, and means operative by engagement with the wrapper being folded and drawn outward to tilt the hopper to paste applying position.

12. In a wrapping machine, a base to support the wrappers, a paste hopper having an

outlet in its bottom, said hopper normally resting by gravity upon the upper wrapper and movable downward by gravity to engage succeeding wrappers, and said hopper 5 being supported for vertical adjustment to a position above the wrappers and pivotally mounted for tilting movement between normal and paste applying positions, and means operative by a wrapper being folded and 10 withdrawn from beneath the hopper to tilt said hopper from normal to paste applying position.

13. In a wrapping machine, a base to support the wrappers, a tiltably mounted hopper having a bottom outlet, the rear wall of the outlet forming a guide to bear upon the wrappers and the front wall of the outlet a scraper to remove excess paste from the wrappers, and an element carried by the 15 hopper and engaged by the wrapper in the folding movement thereof for tilting said hopper to paste applying position.

14. In a wrapping machine, a base to support the wrappers, a tiltably mounted hopper having a bottom outlet, the front and rear walls of the hopper being provided respectively with a scraping edge to remove excess paste from the wrapper and a guiding edge to hold the wrapper down in its 20 movement past the outlet, said edges being movable alternately into and out of working positions by the tilting movements of the hopper, and a crank element operable and guidedly engaged by a wrapper which is being folded to tilt the hopper while the wrapper is being drawn outward from normal to 25 paste applying position.

15. In a wrapping machine, a base for supporting the wrappers, posts rising therefrom, a paste hopper adjustably supported by said posts and having an outlet at its bottom, a closure for the hopper outlet slidably mounted on the front wall of the hopper and including a body of elastic material 30 of circular cross section movable on a line

parallel with said wall, and means for moving said closure into and out of operative position.

16. In a wrapping machine, a base for supporting the wrappers, posts rising therefrom, a paste hopper adjustably supported by said posts and having an outlet slot at its bottom, a stem slidably mounted upon the front wall of the hopper, and a closure for said outlet slot carried by the stem, said 50 closure comprising a body of resilient material of cross-sectional circular form in frictional engagement with said wall and movable on a line parallel therewith.

17. In a wrapping machine, a base for supporting the wrappers, posts rising therefrom, a paste hopper having a bottom outlet and provided with brackets slidably and pivotally engaging said posts, means carried by the brackets to interlock with the posts 60 for holding the hopper in an elevated position, adjustable stops carried by the posts for limiting the tilting movement of the hopper, and means for tilting the hopper from a normal to a paste applying position 65 in the operation of withdrawing a wrapper from beneath the hopper.

18. In a wrapping machine, a base for supporting the wrappers, posts rising therefrom, a paste hopper slidably and tiltably 70 mounted on said posts, said hopper having a bottom outlet provided with a front scraping edge and a rear guiding edge, means for tilting the hopper from a normal to a paste applying position in the operation of withdrawing a wrapper from beneath the hopper, and contact rollers carried by the hopper in rear of its longitudinal center for engagement with a wrapper to limit the pressure of the guiding edge of the hopper out- 75 let upon the wrapper.

In testimony whereof we affix our signatures.

JOHN EDWARD FILLINGAME.

JOSEPH M. RIDEOUT.
